UNITED STATES PATENT OFFICE.

CHARLES W. BUCKHAM, OF NEW YORK, N. Y.

BUILDING.

Application filed April 7, 1927. Serial No. 181,835.

This invention relates to building structures, and has for an object to provide an improved construction and more particularly an improved method of fire resisting construction which may be used for a garage, a school building or other purposes, wherein alternating superposed intermediate floors disposed at half story intervals, interlock substantially in regular order to any desired extent.

Another object of the invention is to provide a building with housed in ramps or stairs enclosed by walls and provided with doors at the points where the stories interlock, the building being so formed that the different stories may be divided into housed in spaces or a combination of housed in spaces and public spaces.

A still further object of the invention is to provide a building which may be used for a garage, wherein the stories interlock, the building being formed so that the different floors may be divided into housed in private garage compartments, or into a combination of housed in private garages and public spaces with enclosed ramps provided with doorways at the points where the stories interlock.

An additional object is to provide a building which may be used for a school building, wherein either ramps or stairs are provided with interlocked stories for the purpose of securing fire-proof protection, while a part of the space of each story being higher than the remaining part, whereby a maximum number of story spaces are provided in a given elevation.

In the accompanying drawings—

Figure 1 is a sectional view through a garage formed according to the present invention, the same being taken on line 1—1 of Figure 2.

Figure 2 is a vertical sectional view through Figure 1 on line 2—2.

Figure 3 is a detail fragmentary sectional view through Figure 2 on line 3—3.

Figure 4 is a horizontal sectional view through a building adapted for use as a school, the same disclosing an embodiment of the invention.

Figure 5 is a vertical sectional view through Figure 4 on line 5—5.

In constructing a building according to the invention, it is aimed to provide a building wherein superposed intermediate floors are disposed at half story intervals and caused

to interlock substantially at the center of the building in regular order, and to any desired extent, with each story interlocked with the story above or below by alternately and oppositely disposed enclosing walls, and with alternately and oppositely disposed means forming door openings. The interpenetrating and interlocking floors present a building structure wherein the floors, ramps and other openings may be housed in and thereby produce what may be termed a fire resisting structure with double fire walls, both for the means of ingress and egress, as well as for the storage space which is a valuable feature when a building is used as a garage by reason of the storage of gasoline or other substances.

Referring to the accompanying drawings by numerals, 1 indicates an outer wall which may be of any desired structure and with any desired number of windows. This outer wall, 75 as shown in Figure 1, encloses a rectangular space, though if desired, the shape of the building could be varied without departing from the spirit of the invention. Arranged within the outer wall 1 are a number of floors, 80 namely, floors 2, 3, 4, 5, 6, 7, 8, 9 and 10. It is evident that a larger number of floors or a less number could be provided without departing from the invention. In connection with the floors, the inventive idea is shown 85 particularly in Figure 2, wherein it will be noted that the floors overlap to an appreciable extent and provide a central overlapped section of flooring. This results in providing horizontal passage-ways 11 and 12 having a 90 certain height and a floor section 13 for each of the floors 2 to 10 inclusive of less height than the passage-ways 11 and 12 and the space exteriorly thereof. The space on each floor next to the wall 1 and the passage-ways 95 11 and 12, are of twice the height as shown in Figure 2, as the flooring space indicated by 13. The overlapping sections as shown in Figure 2 overlap to an appreciable extent and overlap even to a greater extent if desired, 100 though the overlap shown has been found to be desirable for garages and for certain other purposes. Under some circumstances, the overlapping could be appreciably less so as to provide more space with a higher ceiling. 105 The greater the overlap of the floors the greater floor space each floor possesses and, consequently, a greater floor space in a given enclosing wall.

At suitable points there are provided run- 110

ways or ramps 14 which are really inclined passage-ways providing ingress and egress to the respective floors. Under certain circumstances, these ramps may be dispensed with 5 and stairways used but where the building is used for a garage these ramps are particularly desirable as they eliminate the requirement for elevators and at the same time provide an easy path over which the automobiles 10 may travel from floor to floor, going upwardly or going downwardly as desired. The various floors may be left open for the storage of automobiles at any desired place or if preferred, the floors could be housed 15 in and divided into rooms with doors for presenting private garages. A desirable structure is shown in Figure 1, wherein the outer space 15 on each of the floors is used as a public storage space for automobiles. It 20 will be noted that a number of supporting standards 16 are used adjacent this space. At each end of the building in the low ceiling section 13, is arranged walls 17 and 18 respectively, whereby private garages are 25 presented, said garages having suitable doors 19 and 20. Between the ramps 14 there is also provided suitable division walls 21 so that private garages 22 and 23 are presented and a storage space or public garage 30 space 24 is provided. By providing these private garages at this point or some other point, one or more cars may be stored out of possible contact with other cars and also 35 protected against thieves and careless workmen.

As indicated in Figure 3, an automobile 40 may be driven from the street 25 directly through the door 26 onto the bottom floor 2, and from thence may pass downwardly on the lower ramp 14 to a basement floor 2' or 45 may pass upwardly to floor 3 or any of the other floors as desired.

In Figures 4 and 5, a modified form of the 50 invention is shown to that illustrated in Figures 1 and 2. In this form of the invention, the inventive idea has been incorporated in a school building. In the building illustrated in Figures 4 and 5, it will be noted that the central section 13' has low ceilings whereas the outer sections 26 and 27 have high ceilings. The sections 26 and 27 are adapted to be used as classrooms and for certain halls, while the floor space on section 13' will be 55 used for cloakrooms, teachers' rooms, toilet rooms, storage rooms and the like. As indicated in Figure 5, a person may enter from the street 28 and pass through a door 29 onto the floor 30. From the floor 30 the person may pass upwardly along the ramp 31 or 60 downwardly over the ramp 31'. When passing downwardly, the person may pass into the hall 32 and from thence into the assembly room or auditorium 33. An auxiliary ramp 31'' is provided and extends from the 65 hall 32 downwardly into the basement 34.

As indicated in Figure 4, the floor space 35 acts as a hall and opens through suitable doors into the classrooms 36 and 37. This hall also opens into auxiliary halls 38 and 39 in section 13'. The auxiliary halls 38 and 39 may open into suitable rooms 40 and 41. One of these rooms is preferably in communication through doors 42 and 43 to the classrooms 36 and 37 so that this particular room may be used as a cloakroom. The other 75 rooms may be used for other purposes as desired, as for instance, teachers' rooms, storage rooms and toilet rooms.

In Figure 4, the ramp 31 is indicated as ending on the floor 35 while the ramp 31' 80 ends on the floor or hall space 32 which is below the floor 35. The floor in rooms 36 and 37 is on the same level as the floor of hall 35'. The same is true in regard to hall 35', namely, the classrooms 36' and 37' are 85 on the same level as the hall 35'. This same arrangement is carried throughout the building as illustrated in the drawing, and is usually the preferred arrangement, though some changes might be provided to take care 90 of special circumstances. It will be noted that the low ceiling section 13' takes care of the ramps, cloakrooms, teachers' rooms and the like, while the classrooms have double the ceiling space which is desirable by reason of the large number of persons in one room. The auditorium 33 has been shown with an inclined floor but this could be a horizontal floor and also the auditorium 95 could be constructed in different ways without departing from the invention, which primarily consists in the overlapping of the floors and the various means of ingress and egress, including the ramps or stairs. If 100 desired, instead of using the ramps, stairs could be used or even elevators and the same saving of floor space would be present. The drawings have shown the building as being above grade, but if desired, the overlapping floors could be used in connection with a 105 building below grade and the ramps and other parts caused to function in the same manner. Also, in regard to the school building shown in Figures 4 and 5, the cloakrooms may open directly from the classrooms 110 and the auxiliary halls 35 and 35' dispensed with.

What I claim is:

1. A garage building, including outside, 110 end and side walls, a plurality of substantially horizontally positioned floors extending from said side walls and overlapping for a certain distance adjacent the center of the building, a series of ramps connecting said floors, said ramps being positioned at the point where the floors overlap and spaced from said walls, means forming enclosures 115 acting as private garages positioned between the respective ramps and said end walls, means between said ramps forming enclosed 120

private garages, said ramps being spaced from said side walls, means spaced from said ramps for providing restricted parking spaces adjacent said side wall, said parking spaces being spaced from said private garages and said ramps whereby connecting floor space passage-ways are formed connecting said ramps.

2. A building including an outside enclosing wall having side wall members and front and rear wall members, a plurality of horizontal floors extending from two opposite wall members, said floors being spaced apart a certain distance at the said two opposite wall members and interpenetrating and interlocking adjacent the center of the building with the floors at the interlocked portions half the distance apart that they are at the said two opposite wall members, means forming substantially enclosed rooms adjacent the said two opposite wall members, and means forming smaller enclosed spaces in said interlocking portions and enclosed ramps presenting means of ingress and egress positioned within the space of said interpenetrating and interlocking floors.

3. A building, comprising outer enclosing walls, a group of superposed floors extending from one of said walls toward the opposite wall and overlying a part of the ground area within said outer walls, a second group of superposed floors extending from said opposite wall toward the first mentioned group of floors and overlying another part of the ground area within the outer walls, a third group of superposed floors intermediate the first two groups of floors overlying the area between the first two groups of floors, alternately and oppositely disposed vertical walls interlocking the third group of floors with the first two groups of floors, the alternating floors of the third group of floors being aligned with the first and second group of floors alternately, and means of ingress and egress traversing said third group of floors.

4. A building structure, including enclosing end walls and side walls, a plurality of superposed floors overlying an intermediate part of the ground area within said walls, said floors extending from one wall to the opposite wall and spaced from the remaining walls, a group of superposed floors on each side of said first mentioned group of floors, said second group of floors extending from said remaining walls to the first group of floors and alternately merging into said first group of floors and walls at the junctures of the first group of floors with the second group of floors for interlocking the various groups of floors, said last mentioned walls having alternating and oppositely disposed openings, means forming ingress and egress to and from the respective floors, said means being located within the first group of floors and interlocking therewith, and means forming

passage-ways connecting said means of ingress and egress.

5. A building structure including outside walls having side and end walls, a first series of horizontal floors extending from one of said walls toward the opposite wall with the inner edges falling short of said opposite wall, a second series of horizontal floors extending from said opposite wall and projecting to a point beyond the inner edges of the first series of floors, but with their inner edges falling short of said first wall, said second series of floors being spaced approximately half way between the first series of floors, a pair of inner vertical walls, one of said inner walls being positioned at the inner edges of the first series of floors, and the other inner wall being positioned at the inner edges of the second series of floors for dividing the half stories formed by the superposed portions of the respective series of floors from the remaining portions of the respective floors to present a substantially isolated group of floors forming half stories between the remaining floors forming full height stories, and means of ingress and egress to all of said floors.

6. A building structure, comprising outer walls, a plurality of groups of horizontal floors staggered vertically, the planes of the floors of one group for a certain intermediate distance lying in planes interjacent the planes of the floors of another group and separated therefrom by vertical planes of dividing walls to form a series of superposed interjacent mezzanine stories lying therein between serving to form groups or series of reciprocatively acting superposed stories with interjacent mezzanines, said dividing walls having alternately and oppositely disposed openings for presenting passage-ways between the mezzanine stories and adjacent floors, and alternately and oppositely disposed inclined planes or ramps positioned within the space enclosed by the dividing walls, said ramps acting as means of entrance and exit to and from said mezzanine floors.

7. A building including outside walls and a plurality of vertically staggered horizontal floors, the said floors interjacent the center of the building being traversed by a group structure comprising bilateral parallel and perpendicular enclosing walls and within the said outside walls, and an auxiliary group of interjacent horizontal transverse floors, the said auxiliary group of floors separated in rows of bipartite interspacings with respect to the opposite interspacings of the staggered horizontal floors on the opposite sides of the said bilateral enclosing walls and thereby forming groups of oppositely staggered horizontal floors with transverse locked interjacent floors therein between, and means coacting with the said floors presenting means of ingress and egress to any floor.

8. A building structure, including a plu-

rality of opposite outer walls, and within the said opposite outer walls a plurality of horizontal floors, the said horizontal floors being spaced apart in parallel rows of bipartite vertical interspacings, and extending transversely across the said building in opposite transverse and bipartite horizontal interspacings, and oppositely with respect to the said outer walls, and the said transverse horizontal floors enclosed and interlocked within the vertical planes of transverse bipartite crossing by means of parallel and perpendicular planes of bilateral transverse structural walls, the said parallel and perpendicular bilateral walls forming right angles with a plurality of the said opposite outer walls, and extending transversely across the said building from one opposite outer wall member to another opposite outer wall member, thereby separating the said building into interjacent enclosed and interlocked sections of oppositely staggered and transverse locked staggered horizontal floors and into interjacent enclosed and interlocked transverse floors and transverse locked into interjacent and enclosed oppositely staggered stories, and a series of sub-dividing partitions on certain of the floors, enclosing parts of the space within the aforesaid bilateral walls and between the opposite outer walls for presenting minor divisions, and the aforesaid bilateral walls having alternately and oppositely disposed openings for presenting passageways between the different adjacent stories, and alternately and oppositely disposed inclined planes positioned within the space enclosed by the said bilateral walls, said inclined planes acting as means of entrance and exit to and from the said different floors.

9. A building, comprising outer walls, and within the said outer walls and interjacent the center of the building, a plurality of transverse horizontal floors, the said floors sepa-

rated vertically with each second floor crossed to an opposite outer wall and transversely crossed and enclosed within the transverse planes of crossing by parallel and perpendicular planes of bilateral enclosing and bonding walls thereby forming groups or series of oppositely disposed lofty stories with interjacent and interlocking mezzanine stories thereinbetween, said transverse and enclosing walls having alternately and oppositely disposed openings for presenting passageways between the mezzanine stories and adjacent floors, and alternately and oppositely disposed inclined planes positioned within the space enclosed by the dividing walls, said inclined planes acting as means of entrance and exit to and from said mezzanine floors. 60

10. A building structure including a plurality of opposite outer walls, and within the said opposite outer walls, a plurality of groups of bipartite horizontal floors, the said floors vertically and oppositely separated in duplex staggered rows and interjacent the center of the building bonded with a transverse group of bilateral parallel and perpendicular planes of enclosing transverse walls and a plurality of duplex groups of bipartite horizontal transverse floors, thereby causing the building to be separated by duplex groups of bipartite co-acting parts into groups of interjacent duplexed and staggered horizontal floors, and into duplex groups of interjacent enclosed and bipartite and transverse locked duplexed staggered stories, the said bilateral walls having alternately and oppositely disposed openings for presenting passageways between the adjacent duplexed stories, and alternately and oppositely disposed inclined planes positioned between the duplexed stories, the said inclined planes acting as means of entrance and exit to and from the said groups or duplexed stories. 75

CHARLES W. BUCKHAM.
